UNITED STATES PATENT OFFICE.

JOSEPH HIRSHSTEIN, OF ST. LOUIS, MISSOURI.

DRAIN.

1,127,246.

Specification of Letters Patent.

Patented Feb. 2, 1915.

Application filed March 9, 1914. Serial No. 823,368.

To all whom it may concern:

Be it known that I, JOSEPH HIRSHSTEIN, a citizen of the United States, and resident of St. Louis, Missouri, have invented certain new and useful Improvements in Drains, of which the following is a specification:

This invention relates to improvements in drains, and has for its object a casting 10 provided with a flanged shield, the entire device embedded so that the top of the grill surface of the drain is flush with the floor line in order to drain the floor where the device is used in connection with shower 15 baths or the like; and the purpose of the flanged shield is to prevent any seepage passing down between the casting and the material forming the floor from seeping through and appearing on the ceiling be- 20 low.

A further object of my invention is to construct a drain which will catch any seepage which might pass between the outer periphery of the casting proper and the material forming the floor and permit it to pass 25 into the drain, thereby preventing any appearance on the ceiling below the connection.

Figure 1, is a side elevation of my invention with a part thereof in section, showing it in its relative position in the floor. Fig. 2, is a top plan view of the drain detached.

In the construction of my invention I 30 provide a drain constructed of a casting 3, its upper end provided with an internal screw thread 4, in which is inserted an externally screw-threaded grill 5. The inner surface of the casting is provided with a 35 shoulder 6, which is designed to limit the downward movement of the grill so that its surface will remain flush and horizontal with the upper edge 7, of the casting. The said casting is also provided with a pro- 40 jecting flange 8, and a portion of the surface of the casting immediately above the flange is screw-threaded as indicated by the numeral 9. Over this screw-thread is 45 inserted a disk 10, which has a flange 11, 50 projecting upwardly a suitable distance forming approximately a basin; the inner horizontal surface 12, of the disk is ar- 55 ranged to be practically in alignment with a plurality of openings 13, formed in the wall of the casting 3, and through which any seepage which might pass down be- 60 tween the casting and the flooring material at the line indicated by the numeral 14, will be drained off into the casting from the flanged disk. 60

The bottom end 15, of the casting is so shaped as to be adaptable for connection to the drain pipe, either by a wipe joint commonly known to the plumbing trade or it may be arranged with screw-threads so 65 that the end can be attached to a pipe by a suitable coupling. This feature however is immaterial as the essential feature of my invention is to arrange a drain to prevent water from seeping down the side of the 70 casting and staining the ceiling below. 70

In placing the drain in position the same is embedded in the floor, which floor in such instances is preferably constructed by laying a bed of tamped cinders, or like mate- 75 rial 16, and on the top thereof, place a layer of concrete 17, and on the top thereof, the usual tiling 18; or in some instances a smooth coating of cement. And when the device is so placed in position in the floor 80 and in order to provide for proper drainage and in order to further prevent any seepage from passing down on the side of the casting and to properly drain off any such seepage which might pass down the 85 side of the casting, I fill the disk with coarse material, such as pebbles, gravel, cinders or the like, as indicated by the numeral 19, and I may if desired place around the casting over a plurality of aper- 90 tures of the holes 13, a ring 20, constructed of some porous material such as a very fine mesh, felt, sponge or other material found desirable, and by such arrangement it would prevent any of the filler in the 95 flanged disk from passing through any of the apertures. And further, in order to prevent leakage and to make an absolute leak-proof connection between the disk and the casting I may place a gasket 21, at the 100 connecting point at the base of the screw-threads 9. In some instances where it is so required and in the event of the concrete becoming cracked I may embed in the concrete a sheet of pliable material such as 105 sheet lead, copper or the like, 22. This sheet may be extended the entire length and width of the space occupied by the shower, and the same may be slightly inclined so that in the event the floor should become 110 cracked and water seep through the cracks it would contact with the sheet and be di-

rected to the flanged disk and be permitted to pass out into the drain through the openings 13.

This device is not only adaptable for drains through which the water is permitted to pass and drain the floor line when used in connection with shower baths but, may be used also in any connection in bath 10 rooms where there might be a possibility of water seeping down between the castings and floor. It is a well known fact that by sudden changes of temperature such as extremely hot and cold water striking the castings that an expansion and contraction takes place which will cause a separation between the bdy of the casting and the material forming the floor in which the casting is embedded. And this crack or space between the two is the one in which water seeps 15 and follows the line of pipe and shows its appearance on the ceiling below by moistening and straining the same, but with my construction of device this detriment is overcome and such seepage is directed into the 20 drain without any detriment.

Having fully described my invention what I claim is:

1. In drains of the class described the combination of a casting, a detachable 30 flanged shield mounted thereon and approximately centrally located, said casting having a plurality of apertures formed in its wall and on a level with the inner surface of the shield; a grill detachably located in 35 the casting, said casting and shield being embedded in the floor; the said grill being flush with the floor line and a ring of porous material located in the shield covering the apertures for permitting any seepage passing down between the wall of the casting 40 and the floor material to escape into and pass out by way of said casting, substantially as specified.

2. A drain of the class described comprising a casting, an integral flange located thereon, a portion of said casting above the flange being screw-threaded, a flanged shield detachably connected to the casting and held on said screw-threads; the wall of the casting 45 provided with perforations arranged on a level with the inner floor line of said shield through which seepage may be discharged into the casting, a detachable grill located in the top of said casting and arranged to be

flush with the floor line when the entire device is embedded in the floor, substantially as specified.

3. A drain of the class described comprising a casting designed to be attached to a drain pipe, a detachable flanged shield located on said casting and attached by leak-proof connection, apertures formed in the wall of the casting and in alignment with the inner horizontal surface of the shield, said device embedded in the floor, a ring of porous material located around the casting over the apertures; a bed of porous material located in the shield whereby any seepage passing down between the casting and the floor will be drained off into the drain pipe 70 without showing on the ceiling below, substantially as specified.

4. A drain of the class described comprising a cylindrical casting, a plurality of apertures formed in the wall thereof and located at intervals apart at approximately the center of said casting; an integral flange formed on the outer periphery thereof, a detachable flange shield resting on the integral flange, a ring of porous material located in 80 the flanged shield and covering the apertures formed in the cylindrical casting; and a detachable grill located in the top of the casting, all of said parts being embedded and incased in the material forming the 85 floor, substantially as specified.

5. A drain of the class described comprising a cylindrical casting, its walls provided with a plurality of apertures, a detachable flanged shield connected to said casting, its 90 floor line being on a level with the apertures, a ring of porous material located around the casting covering the apertures; a bed of porous material placed in the flanged shield through which moisture can freely pass toward the apertures through which said 95 moisture is drained into the casting; all of said parts being incased and concealed in the material forming the floor, substantially as specified.

In testimony whereof, I have signed my name to this specification, in presence of two subscribing witnesses.

JOSEPH HIRSHSTEIN.
